DESIGN FOR A SERVING SPOON

George L. Bumbaugh, Indianapolis, Ind., assignor to Harry S. Burke, Indianapolis, Ind.

Application July 2, 1934, Serial No. 52,429

Term of patent 14 years

To all whom it may concern:

Be it known that I, GEORGE L. BUMBAUGH, a citizen of the United States, residing at Indianapolis, in the county of Marion, and State of Indiana, have invented a new, original and ornamental Design for a Serving Spoon, of which the following is a specification, reference being had to the accompanying drawing, forming part thereof.

Referring to the drawing, Figure 1 is a plan view of a spoon embodying my design;

Fig. 2 is a sectional elevation of same taken in the proximity of line 2—2, of Figure 1;

Fig. 3 is a cross-sectional view taken in the proximity of line 3—3, of Figure 1; and,

Fig. 4 is a cross-sectional view taken in the proximity of line 4—4, of Figure 1.

I claim:

The ornamental design for a serving spoon, as shown.

GEORGE L. BUMBAUGH.
